UNITED STATES PATENT OFFICE.

LEE W. DIGELY, OF RICHMOND, CALIFORNIA, ASSIGNOR, BY MESNE ASSIGNMENTS,
TO STANDARD OIL COMPANY OF CALIFORNIA, OF SAN FRANCISCO, CALIFORNIA,
A CORPORATION OF DELAWARE.

CAN PAIRING AND INCASING MACHINE.

Application filed July 20, 1925. Serial No. 44,849.

The invention relates to system of and apparatus for pairing casing containers, and is more particularly directed to a system and apparatus for positioning containers in predetermined positions upon a conveyor in groups or pairs, which containers, when grouped, are conveyed along a conveyor, and actuating mechanism to release a casing which fits the containers so grouped, and which groups of containers so placed are conveyed to a point of use or storage.

In casing and packing containers for oil, such as petroleum distillates, gasoline or motor oils, it is necessary that the containers be positioned in the casing in exact position or positions controlled by shipping regulations. Such positioning of containers in cases, when manually performed, entails great labor and expense so that such ordinances and regulation have materially increased the cost of casing and packing such containers and have consequently increased the cost of the articles cased to the purchaser.

This invention is directed to a system for automatically pairing and placing in the correct position in pairs the containers which are to be cased so that the same conform with the ordinances as to shipping and transportation, and which system of inexpensive operation and maintenance enables the packer of such containers to greatly reduce the cost of such packing.

It is an object of this invention to provide a system of pairing containers received in a continuous line and position such containers so that a casing may be fitted thereover.

It is an object of this invention to provide an apparatus for automatically arresting the continuous delivery of containers at a predetermined point, and to segregate the containers as the same are delivered to a pairing and positioning apparatus so that the same are delivered from such pairing and delivering apparatus in pairs positioned to be packed.

It is an object of this invention to provide an apparatus for casing the containers so paired in which the travel of the containers operates automatically to permit a casing to be inserted thereover to enclose the containers.

It is an object of this invention to provide a system of casing containers in pairs in predetermined positions, when the containers are received from a conveyor on their sides, pairing the containers so received and rotating the containers into an inverted position while paired so that a casing may be fitted thereover.

It is an object of this invention to provide a system and apparatus for casing oil containers having filling openings so that the filling openings of a pair of containers are at diagonally opposite points, and which containers are delivered to a point where a casing may be fitted thereover.

It is an object of this invention to provide an apparatus for receiving a plurality of containers from a conveyor, which containers are positioned on their sides and which apparatus will operate to turn each alternate container through a half-turn, which container, when turned, will be paired with a container which has not been turned, and an apparatus for tipping the containers over into an inverted position on a second conveyor and then causing each pair of cans to engage with a wooden case so that the case drops down over each pair of containers.

Other objects and advantages of this invention will be apparent from the following detailed description of a preferred embodiment thereof, as illustrated in the accompanying drawings.

In the drawings:

Fig. 1 is a side elevation, partly broken away, of a container casing and pairing apparatus embodying this invention, illustrating a portion of the apparatus broken away.

Fig. 2 is a side elevation of a portion of the container casing and pairing apparatus broken away from Fig. 1.

Fig. 3 is an enlarged top plan view of the selective receiving apparatus embodied in this invention and illustrating also in top plan view one of the rotating or positioning members.

Fig. 4 is an enlarged side elevation of the section of the apparatus illustrated in Fig. 3.

Fig. 5 is an end elevation of the selective container receiving apparatus illustrated in Fig. 3.

Fig. 6 is an enlarged top plan view of the

second rotating or positioning element illustrating also a balanced receiving platform for receiving the containers from the positioning members.

5 Fig. 7 is a side elevation of the section of the apparatus illustrated in Fig. 6.

Fig. 8 is a top plan view of the container inverting mechanism embodied in this invention.

10 Fig. 9 is an end elevation of the section of the apparatus illustrated in Fig. 8.

Fig. 10 is a side elevation of the casing apparatus embodied in this invention, illustrating a pair of containers properly positioned

15 on the conveyor and engaging a casing to cause the same to drop over the pair of containers.

Fig. 11 is a top plan view of the position of the apparatus illustrated in Fig. 10.

20 Fig. 12 is an end elevation of the casing apparatus illustrated in Fig. 10.

The preferred embodiment of this invention comprises the following units: A selecting and spacing unit A; a positioning or 25 rotating unit B; a pairing unit C; an inverting unit D; and a casing unit E, which are operatively connected through conveyors in the order named. From the casing unit 30 E the containers in an inverted position covered with a casing or box are delivered to a box nailing machine and hence are conveyed to a point of storage or shipment.

The unit A, which is termed the selecting and spacing unit, receives the containers 35 from a conveyor 1 which is preferably a gravity conveyor and delivers the containers to the unit A with their outlets 2 in a predetermined position, as illustrated in Fig. 1. The unit A is preferably of the following 40 construction and comprises a pusher member 3 which pushes the containers from the conveyor 1 when the same are released and it is desired to deliver one of such containers to the balanced platform 4. The spacing and selecting unit A is driven by an electric 45 motor 5 by the conveyor chain 6 of the casing unit E. A drive chain 7 connects the electric motor 5 with a sprocket 8, which sprocket is rigidly secured to the shaft 9. Secured to the shaft 9 is a pair of larger 50 sprockets 10, which sprockets 10 carry a roller chain conveyor 11, which conveyor also travels over sprockets 13 at the opposite end thereof.

55 The sprockets 13 are rigidly secured to a shaft 14 which carries a sprocket 15, which sprocket 15 is connected by means of a drive chain 16 to a sprocket 17 secured to the shaft 18. A pair of sprockets 19 rigidly secured to the shaft 18 drives the conveyor 58. The conveyor 58 also travels over sprockets 21 and 22. The sprockets 22 are rigidly secured to a shaft 23, which shaft 60 drives the spacing and selecting unit A. 65 Two cams 24 and 25 are secured to the shaft

23. A pair of rollers 26, 27 ride upon the cams 24 and 25 and carry yokes 28 and 29 which yokes are pivoted respectively at the points 30 and 31 of the frame 32 of the unit A.

70 Containers from the conveyor 1 are stopped by the unit A as heretofore described, which unit A comprises a pair of short belt conveyors which pass over pulleys 33 and 34 and a roller 35. The pulleys 33, 75 34 are secured to shafts 36 and 36^a. The shaft 36 carries a friction clutch 37 which is driven by the shaft 23 in the following manner:

80 A sprocket 38 is rigidly secured to the shaft 23 and is connected by means of an eccentric pin 39 to an arm 40, the arm 40 being connected as illustrated at 41 to a toggle 42, this toggle being pivoted at the pin 43 to the frame 32 of the unit A. The 85 toggle 42 is pivotally connected at the pin 44 to the clutch operating arm 45, which clutch operating arm 45 is connected to a clutch collar 46. The clutch operating arm 45 is pivoted at a point 47 to an arm 48 90 which extends from the frame 32 of the unit A.

95 The clutch 37 is diagrammatically illustrated as comprising two discs 49 and 50, the disc 50 being loosely journaled on the shaft 36 and a chain 51 drives the disc 50 from the sprocket 38 by means of a sprocket 52 which is rigidly secured to a collar which forms an extension of the disc 50. The disc 49 is rigidly secured to the shaft 36 by 100 a key (not shown) which passes through a keyway formed in the interior bore of the disc 49 to permit the disc 49 to travel along the shaft 36. A spring 53 mounted between the collar 54 and the collar 46 urges the 105 collar 46, and hence the disc 49, into engagement with the disc 50. On each rotation of the shaft 23, it will therefore be apparent that the discs 49 and 50 of the clutch 37 are 110 engaged, and the short belt conveyors of the arresting unit 3 are therefore rotated and stopped alternately.

115 The cams 24 and 25 operate arresting arms 55 and 56; the arresting arm 55 prevents the containers traveling by gravity from the conveyor 1 onto the balanced platform 4 until such arm 55 is rotated or moved from the arresting position by means of the cam 24 so that when the arm 55 is elevated from the 120 arresting position the short belt conveyors of the unit A operate to push a second container against the first container thus forcing said first container on the rollers 57 of the balanced platform 4, and at this time the arresting arm 56 is in position to engage 125 the forward edge of such a container and prevent the same from traveling onto the conveyor 58 of the positioning unit B. The arm 56 arrests the motion of the container and then quickly releases the container so 130

that when a lug 59 mounted on the conveyor 58 engages such container, the same is conveyed along the conveyor 58 to the positioning unit B, as will be hereinafter described:

5 It will be seen that the container will pass from the short belt conveyors of the arresting unit 3 to the rollers 57^a and 57^b where it will remain at rest against the arresting arm 55 until pushed on to balanced platform 4 by a second container arriving from said short belt conveyors. The rollers 57^a and 57^b are inclined at the same angle as the conveyor 1 but the containers are prevented from moving forward by gravity by 10 means of an arm 55^a which is pivoted at one end to the frame 32 and is depressed at its other end by means of a spring and plunger 55^b, thus pressing said arm 55^a against the top of the container which remains stationary 15 until pushed forward by another container arriving from the short belt conveyors.

The platform 4 which carries the rollers 57 is pivoted at the rod 60 to the frame 32 20 of the unit A. The rollers 57 are of short length to permit the conveyor 58 to pass through the intermediate portion of the platform 4. A pair of weights 61 are adjustably secured to arms 62, which arms are 25 secured to the rear portion of the balanced platform 4. The platform 4 is balanced so that when the container drops upon the rear end 63 thereof, the container drops lightly from the conveyor 1 over which it has been 30 pushed by means of the short belt conveyors of the unit A. The second arresting arm 56 prevents the container from running forward upon conveyor 58 until a lug 59 is in contact with the rear of said container at 35 which time the arm 56 is raised by means of arm 29 actuated by cam 25. As soon as the container has been pushed on conveyor 58 by lug 59 the balanced platform 4 is elevated to its original position with the short 40 rollers 57 slightly below the level of the rollers 57^a of conveyor 1. This return motion of platform 4 is effected by means of 45 the counterbalances 61 on arms 62.

The container engaged by the lug 59 50 travels along the conveyor 58 to the positioning unit B, which positioning unit B comprises a pair of rotatable units 65 and 66. When the first container of the pair is delivered from the unit A, the rotatable units 55 65 and 66 are in the position illustrated in Fig. 1, at which time the container is engaged by the square shoulders 67 of the first unit and rotates the unit 65, which rotation 60 of the unit 65, in combination with the square shoulders 67, rotates the first container through ninety degrees to the position illustrated at 68. The lug 59 then conveys the container to the second rotatable unit 66, where the same engages the square shoulder 69 and rotates the unit 66, and the

container is in a like manner rotated through ninety degrees to the position illustrated at 70.

From the rotatable unit 66 the first container is delivered to the pairing unit C, 70 which comprises a balanced platform 71 which is inclined upward from the conveyor 58 so that the first container is caused to travel upward to a point near the delivery end of the balanced conveyor 71 until the 75 lug 59 passes under the container. The second container of a pair is likewise engaged by a lug 59 on the conveyor 58 and is carried through the curved surfaces 72 and 73 of the rotatable units 65 and 66 respectively 80 and causes these units to rotate through ninety degrees, which rotation thereof, however, does not cause the second container to rotate, but leaves the same in the position in which the same were delivered to the conveyor 58. The second container is delivered from the second rotating unit 66 on the inclined balanced platform 71 and when the same is driven toward the said end of such a platform 71 by means of a lug 59 of the 85 conveyor 58, the pair of containers overbalances the balanced conveyor and the same drops at the delivery end to approximately the elevation of the conveyor 58 so that the lug 59 pushing the second container causes 90 both containers of the pair to travel along the conveyor 58, the second container having engaged the first container. It will be seen that the counterbalanced platform 71 95 would tend to rise as soon as the first container is pushed off and the weight upon it thus reduced by one half, thus permitting a separation of the paired containers. In order to prevent said platform from rising 100 before both containers have been removed by a lug 59, a spring plunger having a roller foot is provided as at 71^a attached to the conveyor frame just above and slightly forward of the end of platform 71. This 105 plunger 71^a engages the top surface of the containers as they are pushed forward by lug 59, thus preventing the elevation of platform 71 until the second container has passed off of said platform 71 and is again upon conveyor 58. This same result might be 110 effected by making the length of platform 71 such that, with respect to a given weight 82, and arm 83, one container at the forward end of platform 71 would offset the weight 82 and prevent platform 71 from rising. It is preferred, however, to use the spring plunger as described above.

The rotatable units 65 and 66 are preferably of like construction and comprise a pair of star wheels 74 rigidly secured to shafts 75, which shaft 75 has a square collar 76 secured thereto, which collar 76 presents four flat surfaces 77 which are engaged by means of flat springs 78 to prevent the star wheels 74 from rotating except when the 125

same are engaged by the containers. The springs 78 are secured to a transversely extending member 79 which is secured to the framework of the unit B as illustrated at 80.

5 The platform 71 is balanced by means of a pair of weights 82 which are adjustably secured to arms 83 which arms 83 are secured to the side members 84 of the platform 71. The arms 83 are pivoted at a rod 10 to the frame members 86 of the unit C.

The containers, paired and positioned, are conveyed by means of the conveyor 58 to the inverting unit D, and are inverted in the following manner.

15 A second conveyor 11 is positioned to one side of the conveyor 58 and adjacent thereto, and at a lower elevation than the conveyor 58, as is shown in Fig. 9. A pair of containers travel along the conveyor 58, engage

20 a turning bar 88 which is secured to the frame members 89 at one side of the conveyor 58 and extends across the conveyor at an angle to the travel of the conveyor 58 so that the containers in the pair engage at

25 their rearward edges the surface 90 of the turning rod 88 and are moved toward the edge of the conveyor 58 which is adjacent the conveyor 11. When the containers are moved toward the edge of the conveyor 58

30 and over the edge thereof, the same drop on the conveyor 11, as is illustrated in Fig. 9. A retaining structure 91 is provided to prevent the containers from rotating over and off the conveyor 11.

35 The containers so inverted are conveyed along the conveyor 11 by means of a lug 87 similar to the lugs 59 to the casing unit E, which unit E is preferably of the following construction and mode of operation:

40 A gravity conveyor 92 conveys cases or boxes 93 from any suitable point, such as a box factory or the like. The forwardmost case 93 is arrested in its travel along the conveyor 92 by means of a pair of arms 94,

45 which arms 94 project inwardly over the conveyor 92 a slight distance and engage the outward edges of the case 93. The arms 94 are curved as illustrated at 95 and are pivotally connected to a balancing arm 96

50 by pins 97, the balancing arm functioning to maintain equal projection of the inner ends of the arms 94 in the path of the cases 93. The arms 94 are rigidly secured to pins 98, which pins are pivotally supported at the bearing members 99. Rigidly secured to the pins 98 are toggle links 100, which toggle

55 links are secured at their ends to links 101, which links 101 are connected at their inner ends by means of a tension spring 102, which spring urges the inner ends of the bars 94 into position to engage the edges of a case 93.

60 The opposite arms of the toggle links 100 provide releasing arms 103 which are in position to be engaged by the forward container 65 of the pair which is traveling along the con-

veyor 11. The arms 103 are inclined in the direction of travel of the containers so that the containers when they engage the edges of the arms 103 spread such arms outward against the tension of the spring 102 to release the arms 94 from engagement with the case 93. At the same time, the upper edge 104 of the forward container engages the inner edge 105 of the case 93 and pulls the case 93 along from the equally inclined platform 106 until the rearward edge 107 thereof drops off the far edge of such platform 106, so that in this position the case 93 drops upon the paired containers.

70 It will be obvious that means must be provided for centering the case 93 so that the same will drop over the containers. Such means are provided by the guide rails 108, which guide the cases 93 into position directly over the containers. Guide rails 109 guide the paired containers into a central position on the conveyor 11 upon which the same are carried through a casing unit E. The containers in the inverted position with a case 90 dropped thereover leave the casing unit E on the conveyor 11 and are delivered from the conveyor 11 to any suitable place of delivery, such as another turning unit such as the unit C, where the same are turned right side up and placed upon a gravity 95 roller conveyor which carries the case and containers to a nailing machine, where the top is nailed upon the case, or the paired containers in the inverted position with the case fitted thereover, may be delivered to any other desired position or point.

95 Briefly stated, the operation of the system is as follows:

100 Containers, received from the conveyor in predetermined positions pass through the selecting and spacing unit A which spaces the containers apart a sufficient distance to permit the first container to be rotated to the desired position by means of a positioning unit B and permit the second container to travel through such a unit B after the first container without being affected thereby. The containers are again collected in the pairing C and leave the pairing unit to an inverting unit D where the same are inverted on a conveyor in which inverted position they are carried to a casing unit E, where the paired containers in the inverted position operate to release a casing received from a gravity conveyor and drag the same over into position to permit the same to fall over and cover the pair of containers. From this point the paired containers with the case fitted over them are delivered to any desired position or point of use.

110 Having fully described a preferred embodiment of this invention, it will be understood that it is not intended that the same should be limited to the exact and detailed construction herein set forth, which may ob-

viously be varied in detail without departing from the spirit of the invention, as set forth in the appended claims.

I claim:

5. 1. In a can pairing and incasing machine, the combination of a conveyor along which the cans to be incased and paired are conveyed on their sides, means for pairing the cans so conveyed, means for rotating the cans to an inverted position while paired, and means for fitting a casing over the said cans as paired.

10. 2. In a can pairing and incasing machine, the combination of a conveyor along which a plurality of cans are adapted to be conveyed, means for rotating each alternate can through 180°, means for selectively pairing the cans so conveyed, and means for fitting the casing over the cans so paired.

15. 3. In a can pairing and incasing machine, the combination of a conveyor along which cans to be paired and incased are conveyed on their sides, means for selectively pairing the cans so conveyed, means for inverting the cans so paired, and means for fitting a casing over the cans so paired.

20. 4. In a can pairing and incasing machine, the combination of a conveyor adapted to convey a plurality of cans, means for rotating each alternate can through 180°, means for selectively pairing the cans so conveyed, and means for fitting a casing over the cans so paired.

25. 5. In a can pairing and incasing machine, the combination of a conveyor, means for selectively pairing cans into predetermined positions, means for inverting the cans as paired, and means for fitting a casing over the said cans.

30. 6. In a can pairing and incasing machine, the combination of a conveyor adapted to convey a plurality of containers having filling openings at corresponding corners, means for selectively pairing the cans on the conveyor with their filling openings at diagonal corners of each pair, and means for fitting a casing over the cans so paired.

35. 7. In a can pairing and incasing machine, the combination of a conveyor along which cans having filling openings at their corresponding corners are adapted to be conveyed, means for selectively pairing the cans with their filling openings in predetermined positions, means for inverting the cans, and means for fitting a casing over the cans so paired.

40. 8. In a can pairing and incasing machine, the combination of a conveyor along which a plurality of cans having filling openings are adapted to be conveyed, means for selectively pairing the cans with their filling openings in diagonal opposed positions, and means for fitting a casing over the cans so paired.

45. 9. In a can pairing and incasing machine,

the combination of a conveyor along which a plurality of oil cans are adapted to be conveyed with their filling openings in corresponding positions, means for pairing the cans so conveyed, means for rotating each alternate can so that the filling openings of the cans of each pair are in opposed positions, and means for fitting a casing over the cans so paired.

50. 10. In a can pairing and incasing machine, the combination of a conveyor along which cans having filling openings are adapted to be conveyed with the filling openings of the said cans in corresponding positions, means for rotating each alternate can so that its filling opening is in a position opposed to a non-rotated can, means for pairing the can so conveyed, and means for fitting a casing over the can so paired.

55. 11. In a can pairing and incasing machine, the combination of a conveyor along which a plurality of cans are adapted to be conveyed, means for rotating each alternate can through substantially 180°, means for pairing the cans so that one rotated can is paired with one non-rotated can, means for inverting the cans, and means for fitting a packing case over the cans so paired.

60. 12. In an apparatus of the class described, the combination of a conveyor along which a plurality of cans are adapted to be conveyed, means for separating the cans on the conveyor, means for rotating each alternate can through substantially 180°, means for pairing the cans on the conveyor, means for inverting the cans, and means for fitting a casing over the cans so inverted.

65. 13. In an apparatus of the class described, the combination of a conveyor adapted to support a plurality of containers, means for separating the containers on the conveyor, means for rotating each alternate container through 180° on the conveyor while the said containers are separated, and means for pairing the containers on the conveyor.

70. 14. In an apparatus of the class described, the combination of a conveyor adapted to support and convey a plurality of containers, means for arresting the motion of the containers on the conveyor, means for separately delivering the containers from the first said conveyor to the second said conveyor, means on the second conveyor for rotating each alternate container, and means for pairing one rotated container with one non-rotated container.

75. 15. In an apparatus of the class described, the combination of a conveyor adapted to convey a plurality of containers, means for separating the containers on the conveyor, means on the conveyor for rotating each alternate conveyor to substantially 90°, means on the conveyor for rotating the said containers through a second 90°, said means being inoperative when the second container

of each pair is passing along the conveyor to rotate the said second container, and means for pairing the containers on the conveyor.

16. In an apparatus of the class described, the combination of gravity conveyors adapted to convey a plurality of containers, means mounted on the conveyor for arresting the motion of the containers, driven means adapted to periodically drive a container from the conveyor to a second conveyor, means mounted on the second conveyor for rotating each alternate conveyor through 180°, which means are inoperative to rotate the second container of each pair delivered from the said conveyor and which second container operatively engages the said rotating means to rotate the same from the non-operative to the operative position, and means mounted on the said second conveyor for pairing a rotated with a non-rotated container.

17. In an apparatus of the class described, the combination of means for conveying a plurality of containers, means mounted on the conveyor for pairing the said containers, means for inverting the containers onto a second adjacent conveyor, means on the said second conveyor for arresting the motion of the container, a casing conveyor mounted over the said conveyor and adapted to support the casings in position to be engaged by the forward edge of the container as the same are driven along the second said conveyor so that the containers pull a casing from the casing conveyor over themselves.

18. In an apparatus of the class described, the combination of a conveyor, means mounted on the conveyor for pairing containers, means for inverting the containers so paired onto a second conveyor, means mounted on the second conveyor and adapted to engage the said containers while the same are conveyed along the container to resist the travel of the container, a conveyor mounted above the second said conveyor and adapted to convey a plurality of casings, means operatively connected with the

said container, resisting means for holding the casings in position at the end of the said casing conveyor in position to be engaged by the upper edge of the said containers so that when the said containers are driven past the said resistant means, the said casing arresting means is released to permit the containers to draw a casing from the said casing conveyor.

19. In an apparatus of the class described, the combination of a conveyor, means on the conveyor for separating the containers, means for rotating each alternate container, an inclined pivotally mounted pairing rack mounted on the said container on which the said containers are driven to pair the same and which containers when driven up the pivotally supported pairing rack overbalance the same so as to lower the same to the said conveyor, and means mounted on the conveyor for engaging the said containers for driving the same in pairs from the said pairing rack.

20. In an apparatus of the class described, the combination of a conveyor, along which containers having corner filling openings are adapted to be conveyed with their filling openings in corresponding positions, means for arresting the containers on the said conveyor, driven means for periodically driving a container off of the said conveyor to a second container to separate the same, means mounted on the second container for rotating each alternate container, and which means, after rotating the said container, is actuated to a position inoperative to rotate the next alternate container, which next alternate container, as the same is driven along the conveyor, engages the said rotating means to rotate the same from the non-operative to the operative position, and means on the said second conveyor for pairing a rotated with a non-rotated container.

Signed at Richmond, California, this 9th day of July, 1925.

LEE W. DICELY.
